STRING POTATO PRODUCT

Robert J. Heintz, 1828 Woodsboro, Royal Oak, Mich.

Filed Apr. 12, 1962, Ser. No. 69,679

Term of patent 14 years

(Cl. D8—1)

Fig. 1

Fig. 2

Fig. 3

Fig. 4

Fig. 5

FIGURE 1 is a side elevational view showing my design for a string potato product having the longitudinal axis thereof lying in the plane of the drawing;

FIGURE 2 is a top view of the string potato product shown in FIG. 1;

FIGURE 3 is a cross sectional view taken along the line 3—3 in FIG. 1;

FIGURE 4 is a cross sectional view taken along the 4—4 in FIG. 1; and

FIGURE 5 is a perspective view having the longitudinal axis lying in the plane of the drawing and with the string potato product rotated approximately 45°

about the longitudinal axis from the position shown in FIG. 1.

I claim:

The ornamental design for a strong potato product, substantially as shown and described.
